ELECTRIC HAMMER

Thomas J. Murphy, Stamford, Conn.

Application October 22, 1936, Serial No. 106,935

2 Claims. (Cl. 172—126)

This invention relates to an electric hammer and similar electrically operated devices, and has for an object to provide an improved means for reciprocating the hammer element which does not require a large, expensive or complicated auxiliary electrical apparatus.

It is also an object of the invention to provide improved means to maintain the reciprocating element in concentric relation with the magnetic pole members, and to reduce the friction during its travel to a minimum.

Another object is to provide electrical means for reciprocating the element which will give a hard effective blow in proportion to the amount of energy consumed.

With the foregoing and other objects in view I have devised a construction and arrangement, satisfactory forms of which are shown in the accompanying drawing, but it is to be understood that I am not limited to these specific constructions and arrangements, but that various modifications may be employed within the scope of the invention.

In the drawing:

Fig. 1 is a longitudinal section through a hammer mechanism embodying my invention, the section being substantially on line 1—1 of Fig. 2;

Fig. 2 is a transverse section thereof, substantially on line 2—2 of Fig. 1;

Fig. 3 is a partial side elevation with parts broken away of a handle which may be employed for this hammer.

The device as shown comprises two end members or heads 10 and 11 at the opposite ends of a cylindrical shell 12, the heads having flanges in which the ends of the shell are located. The heads are held on the end of the shell by any suitable means such as a plurality of tie rods or bolts 13 extending between the heads within the shell. Located within the shell are laminated magnetic cores 14, these cores extending longitudinally within the shell and having spaced poles 15 extending radially inwardly toward the center. Any desired number of these cores may be used, in the present showing there being eight equally spaced as shown in Fig. 2. These cores are centered within the shell and in proper concentric relation to the axes of the heads 10 and 11 by rings 16 seating in aligned recesses or grooves in the inner surfaces of the heads and the end walls of the cores, the grooves in the heads being preferably V-shaped as shown. Between the inwardly extending poles 15 are located annular coils 17, 18, 19 and 20 of suitable insulated wire.

Within these coils so as to pass through them is a movable or hammer element 21 which is of magnetic material mounted to reciprocate back and forth through the coils. This element is 5 arranged to slide on a central tubular guide 22 which is securely fastened at one end to head 10. In the present instance it has a reduced portion 23 passing through the head with a nut 24 and a lock washer 25 to clamp it in position. 10 The other end of this tubular guide is centered in the head 11 by a cap 26 within a sleeve 27 mounted to slide in a bushing 28 fixed in the head 11. The cap 26 embraces the end of the guide 22 and is itself mounted in the sleeve 27. 15 On guide 22, preferably integral with it, adjacent the head 10 is a flange 29 having a tapered wall or shoulder 30 against which is forced a ring or cap 31 by a heavy spring 32. The other end of this spring is seated in a cup 33 clamped between the shoulder 34 of the guide member and the end wall of the head 10. The cap or ring 31 is spaced from the cup 33 so that it is yieldable toward it by compression of the spring 32, but the member 31 extends inwardly of the flange 29 so as to form a stop or abutment for the end 25 of the element 21. At the opposite end of the guide and slideable on it within the sleeve 27 is another abutment member 35 which projects inwardly a short distance from the inner end of the sleeve 27. Movement of this member 35 is limited by a flange 36 on the member abutting an inwardly extending flange 37 on the inner end of the sleeve 27. Between this member 35 and the cap 26 is a spring 38 tending to move 30 the member 35 inwardly against the flange 37 so that this spring causes the member 35 to protrude somewhat outside or beyond the end of the sleeve 27. This spring is a considerably lighter spring than the spring 32. 35 A drill or other tool 39 is secured in the holder 40 which is centered by means of a projection 41 in the guide 22. This holder as an abutment 42 resting against the end of the cap 26 and this cap has a flange 43 normally held against the end of the sleeve 27 by means of a spring 44 engaging the flange 43 and secured to the cap 11 by any suitable means such as the screws 45. The guide member 22 is preferably hollow and may be provided with a wick or packing 46 to retain a lubricant that is drawn through any suitable located opening 47 to the outside of the guide and thus lubricate its surface. 40 50 55 This central guide means for mounting the reciprocable element or hammer maintains it in centered relation with the operating coils and

the magnetic pole members 14 and reduces the friction during its travel to a minimum. A loose fit of element 21 on the central guide member is not necessary, all that is required being a good sliding fit. Thus the reciprocating member is always properly centered between the magnetic poles. As the reciprocating element is thus supported and guided in the center its outer surface may be located closely adjacent the magnetic poles 15 without touching them, and it will be seen from Fig. 2, that there is plenty of space around the movable element and between the cores for circulation of air as the element reciprocates, thus allowing free movement of the element, as the air is nowhere pocketed where it is compressed to retard movement of the element.

It will be seen that as the movable or hammer element 21 is reciprocated back and forth its movement to the right is arrested by the abutment member 31 and the heavy spring 32, the recoil of which starts the member 21 in the opposite direction. The movement of member 31 is limited by shoulder 30. At the other end of its movement the blow of the member 21 is first against the end of the member 35 which yields so that the main force of the blow is against the end 37 of the member 27 by which it is transmitted through the cap 26 to the holder 40 and thus to the tool 39. The member 35 through the spring 38 assists or starts the return of the hammer element in the opposite direction and thus prevents magnetic sticking of the hammer due to residual magnetism. This central guide continuously assures a uniform gap between the hammer element and the pole pieces. Also as the central guide may be made of a material of high magnetic permeability it assists in lowering the magnetic reluctance of the hardened steel hammer element 21. The hammer element is preferably made of hardened steel to withstand the effect of the hammer blows.

The head 10 also includes a handle 42 connected to the head by suitable braces 49 and 50, one of which as 49, may be hollow to carry the electrical leads or conductors to the coils 17 to 20. This handle may also contain a control switch (not shown) for turning on and off the current to the coils to thus control the operation.

Having thus set forth the nature of my invention, what I claim is:

1. In a motor of the character described, a central guide member, a reciprocable element embracing said guide and mounted to slide thereon, heads for mounting the opposite ends of said member, a sleeve mounted to slide in one of said heads and forming an abutment for said element, a second member mounted to move longitudinally of the guide and normally projecting a short distance beyond the abutment to be engaged by the element prior to its hitting the abutment, a spring retaining the second member in said normal position, a tool holder for receiving the force of the blow on the abutment member, and electromagnetic means for reciprocating the element.

2. In a motor of the character described, a guide member, a reciprocable element mounted to slide thereon, a head mounting one end of said guide, an abutment slideable in the head to receive the blows of the element, a second member movable longitudinally of the guide and normally projecting beyond the abutment to be engaged by the element before it hits the abutment, yieldable resilient means holding the second member in said normal position, a tool holder receiving the force of the blow from the abutment member, and electromagnetic means for reciprocating the element.
